GRID STRUCTURE AND METHOD OF
FABRICATIONFrederick L. Salisbury, Lynbrook, N. Y., assignor
to The Sperry Corporation, a corporation of
Delaware

Application April 10, 1947, Serial No. 740,560

12 Claims. (Cl. 250—27.5)

1

This invention relates to improved electrode structures for electron discharge devices, and more particularly relates to grid structures and the method of making same.

In many types of electron discharge tubes it is desirable to control the flow of an electron beam by a grid structure through which the electron beam passes. By varying the magnitude of an electric potential between the grid and another electrode, such as a source of electrons, it is possible as is well known, to accelerate or decelerate the electrons depending upon the polarity of the potential.

It is generally desirable in such tubes that the grid structure intercept a minimum number of electrons. This permits the maximum number of controlled electrons to pass through the grid to be utilized in the space beyond. Furthermore, the collision of the intercepted electrons with the grid causes the elements making up the grid to become heated. The grid may eventually be destroyed if its temperature rises too high.

It is also very desirable in grid structures that the elements making up the grid be quite rigid and free from mechanical vibrations. Otherwise, the motion of the grid elements may effect the controlled electron beam causing the tube's electrical output to be very unstable.

Finally, it is desirable that the grid be easy and economical to manufacture. This is especially true if the grid is to be made in large quantities in a short length of time.

In one embodiment of a grid constructed in accordance with the present invention all the elements making up the grid are formed from a single ribbon of metal. This ribbon has a series of spaced V-shaped indentations formed in it by suitable dies. The indentations are formed in groups, all those of any one group being of the same size and shape. The indentations of each successive group are made progressively smaller.

The ribbon, after the indentations are formed therein, is then wound in a spiral fashion so that the indentations of each succeeding wrap nest in spaced fashion within the indentations of the preceding wrap. The wound ribbon is then placed in a retaining member which is shaped to fit the aperture in which it is desired to place the grid. The wound ribbon and the retaining member are then placed in a brazing furnace or treated in some other fashion so as to form them into a unitary grid structure.

By making the grid elements ribbon-shaped, with the narrow edge facing the electron source, the number of intercepted electrons is reduced.

2

The cross-sectional area of the grid elements is still large and therefore the grid will be easily able to conduct away undesirable heat, eliminating the danger of high temperature destruction. The mechanical rigidity of such a grid structure is quite high. This is true since none of the grid elements have unsupported ends, all of the elements being formed from a continuous ribbon. Also since the cross-section of the grid elements is long and thin with the long axis of the cross-section parallel to the electron beam, the grid will have considerable resistance to vibration along the electron beam axis. This mechanical rigidity reduces "microphonics" and tends to make the output of the tube much more stable.

By forming all of the elements from a single continuous element, the problems of manufacturing a grid are reduced and an economical method of fabrication is achieved.

20 It is therefore an object of the present invention to provide a grid structure in which the elements making up the grid are formed of a continuous metallic filament or ribbon.

Another object of the present invention is to provide a grid structure in which the elements have no free unsupported ends.

Still another object of the present invention is to provide a grid structure in which the grid elements have a large cross-sectional area without having a large electron beam obstructing area.

A further object of the present invention is to provide a method of fabricating grid structures in which the grid elements are formed from a continuous metallic filament or ribbon.

Other objects and advantages will become apparent from the following specification, taken in connection with the accompanying drawings wherein:

40 Fig. 1 is a perspective view of a grid structure having independent grid elements formed of metallic filaments;

Fig. 2 is a perspective view of another grid structure having independent grid elements formed of metallic ribbon.

Fig. 3 is a perspective view of a metallic ribbon having V-shaped indentations which serve as grid elements.

Fig. 4 is a plan view of a grid structure formed from the indented ribbon shown in Fig. 3; and

Fig. 5 is the plan view of another grid structure formed from an indented ribbon similar to the one shown in Fig. 3.

Referring now to Fig. 1, a peripheral ring 10 is shown which may easily be formed by joining

the ends of a metallic ribbon at joint 11. Joint 11 may be made in any conventional manner as by lapping the ends of the ribbon and brazing or welding them together, or by making a conventional butt-type joint. Peripheral ring 10 is shaped to fit an aperture in an electron discharge tube in which it is desired to place a grid with the electron beam traveling parallel to the axis of ring 10. For convenience, ring 10 is shown as circular in Fig. 1, but it may take the shape of any closed curve.

Grid element 12 is formed by bending a length of metallic filament 13 into an L-shape having equal-length legs 14 and 15. The length of filament 13 is made slightly less than the diameter of ring 10. The free ends 16 and 17 of L-shaped element 12 are then rigidly fastened in any conventional manner, such as brazing, to the inner surface of ring 10, with the bend 30 of element 12 directed toward the center of ring 10. Since legs 14 and 15 are of the same length and ring 10 is circular in shape, the legs 14 and 15 of element 12 are respectively parallel to, and slightly displaced from a pair of orthogonal diameters of ring 10.

Grid elements 23, 24 and 25 are similar to grid element 12. They are formed into L-shapes and are rigidly joined to the inner face of ring 10 all of the legs of the elements being located in the same plane. The spacing of the L-shaped grid elements 12, 23, 24 and 25 is made regular so that the facing legs of adjacent pairs of grid elements are parallel to each other.

A second set of L-shaped grid elements 26, 27, 28 and 29 is formed in the same manner as the elements 12, 23, 24 and 25, making up the first set, but the length of the filaments from which the elements of the second set are formed is shorter than that of the filaments making up the elements of the first set. The free ends 30 and 31 of element 26 are fastened to the inner surface of ring 10 in a manner similar to the free ends 16 and 17 of element 12, the bend 32 of element 26 being positioned along the same radius of ring 10 as the bend 30 of element 12. Thus, L-shaped element 26 nests within L-shaped element 12, corresponding legs of each element being parallel to each other but spaced slightly apart. In similar fashion, element 27 is anchored to ring 10 in a spaced-nesting relationship with element 23, element 28 with element 24 and element 29 with element 25.

The resulting unitary grid structure presents a grid-like face to the electron beam which it is to control, the grid elements presenting a very small obstructing area to the passing electron beam. Nevertheless, the elements have sufficient cross-sectional area so as to be able to conduct away the heat caused by unavoidable collisions of electrons against the electron-beam facing area of the grid elements. This resulting high heat conductance keeps the operating temperature of the grid elements from reaching a dangerous value and possibly destroying the grid structure.

The mechanical rigidity of this grid structure is quite high since each end of the grid element is firmly anchored in the peripheral ring. Thus, the grid elements will be little influenced by mechanical vibrations of the electron tube in which the grid structure is placed, and therefore such vibrations will not affect the stability of the tube's electrical output.

If it is desired to further decrease the electron-beam facing area of the grid elements without lowering the total cross-sectional area of each ele-

ment, the elements may be formed from lengths of metallic ribbon rather than filaments as shown in Fig. 1. Furthermore, the shape of the grid elements may be changed from the L-shape shown in Fig. 1 to other configurations which may permit a greater number of grid elements to be positioned around the inner surface of the peripheral ring if so desired. Also, there is no limitation in the number of grid elements which may be nested within each other. An embodiment having the elements formed in the shape of V's rather than L's is shown in Fig. 2. The elements of this embodiment are formed from lengths of metallic ribbon. Peripheral ring 40 is formed similar to ring 10 of Fig. 1 by bending a metallic ribbon 41 to the shape of the aperture in which it is desired to place the grid structure, and joining the ends of ribbon 41 at joint 42 in any conventional manner. As in Fig. 1, peripheral element 40 is shown for convenience in description as formed into the shape of a circle, although it may have the shape of any closed curve. Grid element 45 is formed by bending a length of metallic ribbon into a V-shape having equal length legs 46 and 47 disposed at an angle slightly less than 90°.

The length of the metallic ribbon from which grid element 45 is formed is slightly less than the diameter of ring 40 and the width of the ribbon is preferably the same as that of ring 10. The free ends 36 and 37 of legs 46 and 47 are firmly anchored to the inner wall or ring 40, the lines where these free ends 36 and 37 join ring 40 being parallel to the axis thereof. The legs 46 and 47 are thus positioned along a pair of equal length intersecting chords of circular ring 40. Grid elements 50, 51, 52 and 53 are formed in the same manner as grid element 45 having the same size and shape and comprise along with element 45 what shall be called the first set of grid elements. These grid elements 50, 51, 52 and 53 have their free ends fastened to the inner wall of ring 40 in the same manner as the free ends 36 and 37 of legs 46 and 47 of element 45. The angular position of the five V-shaped grid elements 45, 50, 51, 52 and 53 making up the first set is made regular so that the spacing between facing legs of adjacent grid elements is maintained constant.

A second set of grid elements 60, 61, 62, 63 and 64 is also formed by bending short lengths of metallic ribbon into V-shapes having equal length legs. The length of the ribbons from which the elements of the second set are formed is slightly less than the length of the ribbons forming the first set of grid elements with the width preferably the same. The angle between the legs of the V-shaped members in the second set is not necessarily the same as the angle between the legs of the grid elements making up the first set, being preferably made smaller, although equal angles can also be used. In Fig. 2 it can be seen that the angle between the legs 65 and 66 of grid element 60 is slightly less than that of grid element 45. The second set of grid elements are anchored to the inner face of ring 40 in the same manner as the elements making up the first set, each of the elements of the second set being positioned in a symmetrical nested relationship with one of the elements of the first set.

A third set of grid elements 70, 71, 72, 73 and 74 is formed by bending shorter lengths of metallic ribbon into V-shapes in the same manner as the preceding two sets of grid elements. The length of the ribbons making up the grid elements in the third set is shorter than the length of the ribbons making up the elements of the sec-

ond set and the width of the ribbons is preferably the same. Again, the angle between the legs of each V-shape members of the third set is not necessarily the same as the angle between the legs of the preceding set of grid elements and again the angle is arbitrarily made smaller. This is seen more clearly by referring to grid element 70 where it can be seen that the angle between legs 75 and 76 of this element is smaller than the angle between the legs 65 and 66 of element 60. As before, each element making up the third set of grid elements is rigidly connected to the inner face of peripheral ring 40 in a symmetrically nested relationship with the other two sets of grid elements, all members of each set being coaxial and co-directed.

The resulting unitary grid structure is thus composed of three sets of V-shaped grid elements, each set comprising five elements. The free ends of each member are rigidly connected to the inner wall of the peripheral ring member, corresponding members of each set being positioned in a symmetrical nested relationship.

Thus it can be seen in the embodiment shown in Fig. 2 that the number of elements making up a set of grid members can vary at will, as can the number of sets used in a grid structure. The electron-beam facing area of the resulting grid structure can be kept to a minimum while permitting the cross-sectional area of the grid elements to be sufficiently large so as to conduct away the heat resulting from the collision of electrons with the obstructing faces of the grid structure. The rigid anchoring of the free ends of each element, and the V-shape of the members contribute to a grid structure in which the elements have a high degree of mechanical stability and are little affected by vibrations of the electron tube in which the grid is placed.

The ribbon-like structure of the grid elements shown in Fig. 2 not only aids in minimizing the electron-beam facing area of the resulting grid structure, but aids in further increasing the mechanical rigidity of the resultant grid. This is true since the long dimension of the cross-sectional area of the grid members is parallel to the electron beam. This tends to reduce to a minimum any bending of the grid elements in a direction along the electron beam, and thus minimizes instability effects due to motion of the grid elements in the direction parallel to the beam.

Although the grid elements making up the grid structures shown in Figs. 1 and 2 are formed from individual lengths of metallic filament or ribbon, all the grid elements may be and preferably are easily and economically formed from a single continuous filament or ribbon. This may be done by making properly spaced indentations in a filament or ribbon, winding the indented filament or ribbon in spiral fashion and then placing the wrapped or wound member in a peripheral ring element, similar to that shown in Figs. 1 and 2. The spiralled member and peripheral element are then treated in any conventional manner, such as brazing or welding, so as to form a unitary structure.

This procedure will be more clearly understood by reference to Fig. 3. This figure shows a ribbon 80, which may be a filament, if desired, in which is formed a first set of equally spaced, V-shaped indentations 81, 82, 83 and 84 separated by spacing portions 85, 86, 87 and 88. All of the indentations of this set are of the same size and shape. A second set of equally spaced V-shaped inden-

tations 91, 92, 93 and 94 is formed in the ribbon 80 slightly spaced from the first set by spacing portion 95. The indentations of the second set are all of the same size and shape, but they are smaller than those of the first set. Spacing portions 96, 97 and 98 separate the indentations of this set. A third set of still smaller equally spaced indentations 101, 102, 103 and 104 are formed in the ribbon 80, slightly spaced from the second set by spacing portion 105. The indentations of this set are separated by spacing portions 106, 107 and 108.

The three sets of indentations may be formed in ribbon 80 in any conventional manner. One way is by pressing ribbon 80 between a suitably shaped punch and matrix.

The ribbon 80 is then wound in spiral fashion with the large indentations of the first set completely occupying the inner wrap. The flat spacing portions separating the indentations of the first set are bowed to give the required curvature of the ribbon. The indentations of the succeeding set are so spaced that, as the ribbon is wrapped closely around the first or inner wrap, the indentations of each succeeding wrap position themselves in symmetrical, nesting relationship with corresponding indentations in the preceding wrap. The bowed or arcuate spacing portions of the ribbon in each wrap between the indentations are in complete contact with similar spacing portions in preceding and succeeding wraps.

A peripheral ring member is then fitted around the outer wrap making contact with the now arcuate spacing portions of the outer wrap. This ring member maintains the spiral shape. The assembled structure is then given a heat treatment, or the like, to weld, braze, or solder or otherwise form together the contacting arcuate portions of each wrap. At the same time the retaining or peripheral ring member is similarly fixed to the arcuate portions of the outer wrap of the spiral. As a result of such heat treatment, the spiraled, indented ribbon and the peripheral retaining member unite to form a unitary grid structure of great mechanical rigidity.

This construction is more easily understood by reference to Fig. 4. In this figure ribbon 80 of Fig. 3 is wound into a spiral, and the spiralled member is then fitted into a ring member 110. Indentations 81, 82, 83 and 84 along with spacing portions 85, 86, 87 and 88 form the inner wrap of the spiral. The second wrap begins with spacing portion 95 whose inner face is in contact with the outer face of spacing portion 85 of the inner wrap. Indentations 91, 92, 93 and 94 along with spacing portions 96, 97 and 98 complete this wrap. Spacing portion 105 whose inner face is in contact with the outer face of spacing portion 95 begins the third wrap of the spiral. This wrap is completed by indentations 101, 102, 103 and 104 along with spacing portions 106, 107, 108 and 109. The inner face of outer ring member 110 contacts the outer face of the spacing portions 105, 106, 107, 108 and 109 of the outer wrap. This ring member 110 maintains the ribbon 80 in its spiral shape until it is formed into a unitary structure. This may be done in any conventional manner as by placing the assembled grid into a welding or brazing furnace and forming a unitary grid structure.

It will be noted, by reference to Figs. 3 and 4, that the first indentations of each set arrange themselves in a symmetrically nested relationship. Thus, after the brazing or welding or like

operation, the corresponding indentations of each set are similar to the grid elements shown in Fig. 2. However, by making the grid elements from a single ribbon rather than by forming a multiplicity of individual grid elements the resulting structure can be made more readily and easily.

The inherent advantages of such a grid structure as shown in Figs. 1 and 2 are also realized in the continuous ribbon grid structure of Fig. 4. The additional advantage, however, of the continuous ribbon type structure is in the ease and economy of manufacture. Using the above suggested method of fabricating the grid structure, there is considerable assurance of uniformity in the resulting products. This is particularly advantageous in the mass production of electron discharge tubes using grid structures if the tubes are to be interchanged in operation. In such cases, there will be little or no change in the static and dynamic operating characteristics of the tubes due to non-uniformity of grid structures.

It will be understood that the apex angles of the V-shaped indentations of the successive sets may be the same or may get smaller toward the outer wrap.

A slightly different embodiment of the grid structure of Fig. 4 is shown in Fig. 5. In this embodiment, the shapes of the indentations forming the grid elements varies from set to set. Also by extending the length of the indented ribbon beyond the last indentation and forming an extra wrap of this extension the separate peripheral element may be dispensed with.

In this structure a metallic ribbon 115 is given a series of curved indentations 120, 121, 122 and 123, preferably of hyperbolic shape, forming the center wrap of a spiralled grid structure along with arcuate portions 124, 125, 126 and 127. The curved indentations 130, 131, 132, 133 of the second wrap are shaped similar to end sections of ellipses. Intermediate arcuate portions 134, 135, 136 and 137 complete the second wrap. The inner faces of the arcuate portions 134, 135, 136, 137 of the second wrap are in close contact with the outer faces of the arcuate portions 124, 125, 126, 127 of the inner or first wrap.

A third set of curved indentations 140, 141, 142 and 143 are semi-circular in shape with equal length, parallel extending legs separated from each other by the length of the diameter of the semi-circular section. These indentations along with intermediate arcuate portions 144, 145, 146 and 147 complete the third wrap of the spiralled grid structure. Arcuate portion 150, which extends from the last indentation 143 of the third set, makes a complete wrap around the spiral and has its free end joined to the point where its opposite end and the connecting leg of indentation 143 form bend 151. By connecting the free end of outer wrap 150 to bend 151 the spiralled shape of the grid structure is maintained, and the structure may then be given a suitable treatment so that the close by contacting arcuate portions may be welded or brazed together to form a unitary structure.

Thus, by extending one end of the ribbon 115 sufficiently beyond the last indentation formed therein, it is possible to form the peripheral element of the grid structure from the same ribbon which forms the grid elements themselves. This permits the entire grid structure to be constructed from a single length of metallic ribbon.

It will be understood that all the indentations

may be shaped according to similar types of curves, if desired, or still other shapes may be utilized.

Hence, by the use of a single metallic ribbon or filament in which a series of suitable spaced indentations are formed it is possible to fabricate a unitary grid structure by winding the indented ribbon or filament in a spiral fashion and suitably forming the resulting spiralled member into a unitary structure, as by a heat treatment which welds or brazes together the contacting portions of the spiralled member between indentations. The indentations are so spaced along the ribbon or filament so that those of succeeding wraps of the spiral nest together.

The spiral shape may be maintained during the fastening operation by placing the spiralled member into a peripheral, retaining member. If desired, an additional wrap may be made by the ribbon and the free end of the ribbon fixed to the beginning of this additional wrap so that the spiral shape will be maintained. The structure may then be given a suitable heat treating or other operation so that a unitary structure results.

The resulting grid structure has a low electron-beam obstructing area, but the grid elements themselves have sufficient cross-sectional area so as to be able to safely conduct away the heat caused by electron collisions. The mechanical rigidity of this structure is quite high since none of the grid elements have free, unsupported ends. If the grid elements are formed from a ribbon-like element rather than a filament, additional rigidity is given along the axis of the spiral.

The indentations may be formed in the filament or ribbon by using dies. This permits a large number of uniformly shaped grid structures to be made easily and quickly.

Therefore, in accordance with the present invention it is possible to easily and economically fashion a grid structure in which the elements making up the grid are formed from a continuous metallic ribbon or filament. The grid elements of such a grid structure have no free, unsupported ends, which permits great mechanical rigidity. Furthermore, the cross-sectional area of the grid elements may be large while the electron-beam obstructing area can be kept quite low. Finally, such a grid structure may be produced in great numbers easily and economically with a high degree of uniformity by forming the grid elements by dies or otherwise from a single elongated metallic member.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A single piece spiral shaped grid structure comprising a ribbon having a first plurality of equal-sized V-shaped indentations therein spaced equally and having their apexes directed toward the center of said spiral, and having a second plurality of smaller equal-sized V-shaped indentations in said spiral spaced from, but in nested relationship with a corresponding indentation of said first plurality.

2. A grid structure consisting of a thin metallic ribbon mounted in a spiral having three wraps,

said ribbon having in its innermost wrap a first series of equally sized V-shaped indentations separated by equal length spacing portions, a second series of V-shaped indentations in the middle wrap of said spiral separated by equal-length spacing portions, said indentations of said second series being smaller in size than those of said first series and nesting within the larger indentations of said first series, the equal-length spacing portions of said middle wrap being in contact with the spacing portions of said inner wrap, and the outer wrap of said spiral being in contact with the equal-length spacing portions of said middle wrap.

3. A grid structure for an electron discharge tube consisting of an elongated metallic member mounted in spiral shape having a plurality of wraps, the innermost wrap having a plurality of substantially equal-sized V-shaped indentations directed toward the center of said spiral, said indentations being spaced from each other by a plurality of equal-length member portions, succeeding wraps of said spiral each having an equal number of V-shaped indentations arranged in nested relationship with the indentations of the innermost wrap, and separated from each other by an equal number of member portions, the indentations of each succeeding outward wrap being of the same size but progressively smaller than the indentations of the preceding wrap, the member portions of each succeeding outward wrap being of the same length but progressively longer than and making contact with the member portions of the preceding wrap.

4. A grid structure for an electron discharge tube comprising an elongated metallic member mounted in a flat spiral shape having a plurality of wraps, the innermost wrap having a plurality of spaced, equal-sized, inwardly directed indentations, succeeding wraps each having an equal number of spaced inwardly directed indentations arranged in symmetrical nested relationship with the indentations of the innermost wrap, the indentations of each succeeding outward wrap being of the same size but progressively smaller than the indentations of the preceding wrap, the connecting portions of each wrap between the inwardly directed indentations thereof being in close contact with the connecting portions between the inwardly directed indentations of the next succeeding outward wrap, and a closed perimeter member positioned around the outward wrap of said spiral, the connecting portions of said outer wrap between the inwardly directed indentations thereof being in close contact with said perimeter member.

5. A grid structure for an electron discharge tube consisting of an elongated metallic member mounted in a spiral shape having a plurality of wraps, the innermost wrap having a plurality of inwardly directed indentations separated by arcuate portions, each succeeding wrap of said spiral having a like plurality of inwardly directed indentations arranged in spaced, nested relationship with the indentations of the innermost wrap and separated from each other by arcuate portions, the indentations of each succeeding outward wrap being progressively smaller than the indentations of the preceding wrap, the arcuate portions of each succeeding wrap making contact with the arcuate portions of the preceding wrap.

6. The method of forming an electron discharge tube grid structure comprising the steps of forming a first series of equal-sized V-shaped indentations in a thin metallic ribbon, the indentations being separated by a first series of equal-length ribbon portions, forming a second series of equal-sized, V-shaped indentations in said metallic ribbon displaced from said first series, the indentations of said second series being separated by a second series of equal-length ribbon portions, the indentations of said second series being smaller in size than those of said first series and the 10 equal-length ribbon portions of said first series being shorter than those of said second series, wrapping said ribbon into a spiral having two wraps, so that the indentations of said second series nest within the indentations of said first series, both being inwardly directed, and so that the ribbon portions of said first series make contact with the ribbon portions of said first series, and joining said first series of ribbon portions to said second series where they make contact.

20 7. The method of forming a grid structure comprising the steps of forming a first series of indentations in an elongated metallic member, the indentations being separated by a first series of spacing portions, forming a second series of indentations in said metallic member displaced from said first series of indentations, the indentations of said second series being separated by a second series of spacing portions, wrapping said elongated member into a spiral so that the indentations of said second series nest within the 25 indentations of said first series, both being inwardly directed and the first series of spacing portions making contact with the second series of spacing portions, fitting said wrapped member into a closed metallic peripheral member such that the spacing portions of said second series make contact with said peripheral member, joining together said first series of spacing portions to said second series where they make contact and said second series of spacing portions to said peripheral member where they make contact.

30 8. The method of forming a grid structure comprising the steps of forming a first series of indentations in an elongated metallic member, the indentations being separated by a first series of spacing portions, forming a second series of indentations in said metallic member displaced from said first series of indentations, the 35 indentations of said second series being separated by a second series of spacing portions, wrapping said elongated member into a spiral having two turns so that the indentations of said second series nest within the indentations of said first series, both being inwardly directed and the first series of spacing portions making contact with the second series of spacing portions, and joining together said first series of spacing portions to said second series of spacing portions where they make contact.

40 9. The method of forming a grid structure comprising the steps of forming a first series of indentations in an elongated metallic member, the indentations being separated by a first series of spacing portions, forming a second series of indentations in said metallic member displaced from said first series of indentations, the indentations of said second series being separated by a second series of spacing portions, wrapping 45 said elongated member into a spiral having three wraps so that the indentations of said first series and the spacing portions of said first series form the innermost wrap, the indentations of said second series and the spacing portions of said second series form the second wrap, and the ex-

11

tended free end of said elongated member makes one complete turn to form the outer wrap, the indentations of said second series nesting in spaced relationship within the indentations of said first series, the spacing portions of said first series making contact with the spacing portions of said second series, and said extended free end making contact with the spacing portions of said second series, and joining together said spacing portions and said extended free end when they make contact.

10. A spiral form grid structure comprising a continuous ribbon arranged to have a plurality of substantially radial portions of equal length and a second plurality of substantially radial portions of equal smaller length, said second plurality being equally spaced from said first portions.

11. A plane spiral grid structure comprising a continuous ribbon arranged to have a first

10

15

20

12

plurality of substantially radial portions and a second plurality of smaller substantially radial portions.

5 12. A plane spiral grid structure comprising a continuous ribbon arranged to have a plurality of substantially radial portions and a second plurality of smaller portions substantially parallel to said first portions.
